UNITED STATES PATENT OFFICE.

CLARENCE G. WING, OF LAKEWOOD, OHIO, ASSIGNOR TO THE SCOTT-ULLMAN COMPANY, OF CLEVELAND, OHIO, A CORPORATION OF OHIO.

DESIGN FOR A LIGHTING FIXTURE.

Application filed February 8, 1926. Serial No. 16,452. Term of patent 3½ years.

To all whom it may concern:

Be it known that I, CLARENCE G. WING, a citizen of the United States, residing at Lakewood, in the county of Cuyahoga and State of Ohio, have invented a new, original, and ornamental Design for a Lighting Fixture, of which the following is a specification, reference being had to the accompanying drawing, forming part hereof, wherein—

Fig. 1 is a front elevation, and Fig. 2 a top plan view of a lighting fixture exhibiting my new design.

I claim:

The ornamental design for a lighting fixture, as shown.

CLARENCE G. WING.
